Primary Examiner—Dominic Simone

(57) CLAIM

The ornamental design for a fashion accessory, as shown and described.

DESCRIPTION

FIG. 1 is a front elevational view of a pair of fashion accessory in use on a shoelace, showing my new design;

FIG. 2 is a front perspective view thereof;

FIG. 3 is a rear perspective view thereof;

FIG. 4 is a front perspective view of a second embodiment of FIG. 2;

FIG. 5 is a rear perspective view of FIG. 4;

FIG. 6 is a top plan view of FIG. 2;

FIG. 7 is a bottom plan view of FIG. 2;

FIG. 8 is a side elevational view of FIG. 2;

FIG. 9 is an opposite side view of FIG. 8;

FIG. 10 is a front elevational view of FIG. 2;

FIG. 11 is a rear elevational view of FIG. 10;

FIG. 12 shows a front elevational view of a fashion accessory when used to decorate a bracelet or wristband; and,
FIG. 13 shows a front elevational view of a fashion accessory when used to decorate a necklace or neckband.

The broken line showing in FIGS. 1, 12 and 13 are for illustrative purposes only and form no part of the claimed design.
